(57) **CLAIM**

The ornamental design for a computer display with integrated camera, as shown and described.

DESCRIPTION

FIG. 1 is a front-right perspective view of a computer display with integrated camera showing a first embodiment of our new design;

FIG. 2 is a bottom-front-left perspective view thereof;

FIG. 3 is a front view thereof;

FIG. 4 is a back view thereof;

FIG. 5 is a left-side view thereof;

FIG. 6 is a right-side view thereof;

FIG. 7 is a top view thereof;

FIG. 8 is a bottom view thereof;

FIG. 9 is a front-right perspective view of a computer display with integrated camera showing a second embodiment of our new design

FIG. 10 is a bottom-front-left perspective view thereof;

FIG. 11 is a front view thereof;

FIG. 12 is a back view thereof;

FIG. 13 is a left-side view thereof;

FIG. 14 is a right-side view thereof;

FIG. 15 is a top view thereof; and,

FIG. 16 is a bottom view thereof.

The broken lines illustrate portions of the computer display with integrated camera that form no part of the claimed design.

The thin, black lines shown in long dashes with intermittent breaks represent shading and/or tangent lines to show contour of the surfaces or curved edges of a computer display with integrated camera, and do not actually appear on the surface of the device.
